CLAIM

The ornamental design for an outdoor fireplace, as shown and described.

DESCRIPTION

FIG. 1 is a perspective view of an outdoor fireplace showing our new design;
 FIG. 2 is an elevational view of one side thereof;
 FIG. 3 is a front elevational view thereof;
 FIG. 4 is a rear elevational view thereof;
 FIG. 5 is a top plan view thereof; and,
 FIG. 6 is a bottom plan view thereof.
 The surface or portion of the article not shown in the drawing or described in the specification form no part of the claimed design.
